UNITED STATES PATENT OFFICE.

RICHARD A. POEHL, OF LA MOURE, NORTH DAKOTA.

MILKING STOOL AND PAIL HOLDER.

Application filed September 18, 1928. Serial No. 306,707.

This invention relates to an improved dairy farm appliance herein entitled a milking stool and pail holder, and it has reference to a structural arrangement wherein these parts are combined into a single structure.

The principal novelty is predicated upon an arrangement wherein the stool is provided with a rigid extension frame which is constructed to accommodate a tilttable pail holding device, manual operating means therefor, and a catch or retainer for said means, wherein the retainer is rigidly mounted on the stool at a point convenient for easy manipulation.

My principal object is to provide a structure characterized by such advantageous features and so made as to insure efficient performance, practicability, compactness and convenience of arrangement of parts, simplicity and other features which permit the invention to fulfill the requirements of a structure of this class.

Referring now to the drawings:—

25 Figure 1 is a top plan view of the complete structure as constructed in accordance with the present invention.

Figure 2 is a side elevation thereof.

30 Fig. 3 is an enlarged fragmentary sectional and elevational view showing certain details of the stool, the pail holder, operating means, and the retaining catch for the operating means.

Fig. 4 is an enlarged view showing the 35 pin and slot connection between the upper pail ring, and one of the frame standards.

Fig. 5 is a rockable connection between the pail holder ring, and one of the frame standards.

40 Referring now to the drawings in detail, in Fig. 2, the stool is generally designated at 6 and the holder at 7. The stool comprises suitably connected supporting legs 8 connected with an annular angle iron 9 carrying the disk-like seat 10 and reinforcing bar 11. Mounted on the stool as shown in Fig. 3 is a depending block 12, carrying a peculiarly shaped casting or fitting 13 which in turn carries a pair of normally 45 diverging catches 14, held apart by an expansion spring 15. This constitutes a feature whose function will be made clear later.

Formed integral with the stool are forwardly extending spaced parallel horizontally disposed rails 16 connected together

with a transverse end piece 17 and forming an extension frame on the stool. Carried by the intermediate portion of the rail is a fulcrum rod 18, and disposed above the rod are upstanding uprights for standards 19 having elongated slots 20 formed therein to accommodate headed studs 21.

These headed studs are carried by a ring 22 which embraces the upper end portion of the pail (not shown).

Disposed below the ring 22 and then pivotally connected by eye bolts 23 with the rod 18, is the disk-like base 24 upon which the pail is placed. This base is provided with a marginal outstanding retaining rim 25.

Referring now to Fig. 3, it will be seen that 26 designates a bracket fastened to the base and provided with a forked portion 27 carrying a pin 28 around which the lower end portion 29 of an operating lever 30 is 75 bent. The upper end of the lever is provided with a finger piece knob 31 to facilitate operation and the intermediate portion cooperates with retaining catches 14.

A frame 32 is also provided and is connected with the ring 22 and the bracket 27. A coiled spring 33 is fastened to the brace at one end and anchored upon the fitting 13 at the opposite end.

With this arrangement, it will be seen 85 that by releasing the retaining catches 14, the occupant of the stool may push or pull the rod or lever 30 to rock the entire holder 7 on its fulcrum. The rocking motion is in a forward and downward direction and is 90 permitted by the pin and slot connection between the ring 22 and the stationary standard 19. Thus, the stool occupant can arrange the pail in a dependable forwardly and downwardly inclined position to the initial starting operation. Then through the medium of the operating means, the holder and pail can then again be righted.

By considering the description in connection with the drawings, it will be seen that 100 I have evolved and produced a novel and compact structure for supporting a special pail holder from a stool and making a single structure thereof, the arrangement being such that the pail holder can be tilted forwardly and downwardly to hold the pail in a corresponding inclined position such as is customary in milking.

The structure is dependable and positive in operation, and is otherwise satisfactory in 110

fulfilling the requirement of the invention in a suitable manner. Hence, a more lengthy description is regarded unnecessary.

Minor changes in shape, size, and arrangement of details coming within the field of invention claimed may be resorted to if desired.

Having thus described my invention, what I claim as new is:—

- 10 1. In a structure of the class described, in combination, a milking stool, a horizontal forwardly extending frame mounted on said stool and provided with a supporting rod, a milk pail holder rockably mounted on said rod, an operating member pivotally connected with said holder, a retaining device on said stool with which said operating member is cooperable, standards on said frame at diametrically opposite sides of the pail holder, and pin and slot connections between the standards and pail holder.
- 20 2. In a structure of the class described, in combination, a milking stool, a horizontally disposed forwardly extending frame on the stool, a supporting rod carried by the frame, a pail supporting base rockably

mounted on said rod and confined within the limits of said frame, a bracket carried by said base, an operating member pivotally connected at its lower end to said bracket, and a manually releasable retaining device carried by said stool, said operating member being cooperable with said retaining device.

3. In a structure of the class described, in combination, a milking stool, a horizontally disposed forwardly extending frame on the stool, a supporting rod carried by the frame, a pail supporting base rockably mounted on said rod and confined within the limits of said frame, a bracket carried by said base, an operating member pivotally connected at its lower end to said bracket, a manually releasable retaining device carried by said stool, said operating member being cooperable with said retaining device, diametrically opposite slotted standards on said frames, a pail embracing ring, stud connections between the rings and said slots, and a brace connection between the ring and said bracket.

In testimony whereof I affix my signature.

RICHARD A. POEHL.
